UNITED STATES PATENT OFFICE

2,062,657

COAL MINING MACHINE

Joseph F. Joy, Marion, Ohio, assignor to Sullivan
Machinery Company, Chicago, Ill., a corpora-
tion of Massachusetts

Application August 11, 1933, Serial No. 684,707

36 Claims. (Cl. 262—28)

My invention relates to mining machines and, in particular, to coal mining machines adapted to cut kerfs in a coal seam.

An object of my invention is to provide a compact and durable coal mining machine capable of being easily maneuvered and adjustable to cut either vertical or horizontal kerfs on any level in a rapid and efficient manner.

Another object is to provide a coal mining machine, the major movements of which are actuated by fluid pressure devices.

Another object is to provide such a machine with a simple, efficient and compact valve system, and with centrally arranged controls at the rear 15 of the machine away from any danger of falling coal, and yet within the reach of a single operator.

Another object is to provide an arrangement of walking jacks whereby the machine may be readily advanced or turned in a small space.

Another object is to provide a vertically yieldable mounting arrangement for the cutter blade and chain.

Another object is to provide such a machine arranged to slide on the mine floor, and a flexible feeding system with precisely controlled feeding drums conveniently arranged at the rear of the machine.

Another object is to provide such a machine 30 with deflecting sheaves at the forward end thereof arranged for adjustable movement longitudinally of the machine for the purpose of balancing the pull on the feed rope and thereby making possible the movement of the machine at right angles to the coal face regardless of the resistance met by the cutter blade.

Another object is to provide power transmission devices whereby a single motor is made capable of actuating the cutting mechanism and 40 also the flexible feeding mechanism regardless of the position in which the machine may be placed.

Another object is to provide such a machine having a cutter head adjusting mechanism which is simple and inexpensive, yet quick and effective.

Another object is to provide safety devices which will prevent injury to the machine in case of its encountering great resistance or obstacles.

Another object is to provide such a machine 50 wherein the weight is precisely balanced by a careful arrangement of the parts, thereby enhancing the ease of turning or pivoting in conjunction with the walking jacks.

Another object is to provide such a machine 55 with vertical adjusting means arranged to cause

the tip of the cutter blade to move through a greater distance than its rear end during vertical movements.

Other objects and purposes will be made apparent from the following description taken in connection with the drawings and appended claims.

In the drawings:

Figure 1 is a side elevation of a coal mining machine embodying one form of my invention, 10 shown cutting a kerf near the floor level.

Figure 53 is a central vertical section as in Figure 42, but with the valve adjusted to permit a flow of fluid in the opposite direction from that of Figure 52.

20

General construction summarized

In general the coal mining machine of my invention in its preferred form consists of a sub-frame or skid plate on which is slidably mounted a main frame reciprocable relatively thereto by hydraulic cylinders. On the main frame is mounted hydraulically operated elevating mechanism culminating in a cutter blade having an endless cutter chain, and the cutter blade itself is independently tiltable by a hydraulic cylinder. 30 Power transmission mechanism connects this cutter head with an electric motor mounted on the main frame, and further transmission mechanism connects the motor with a pair of feeding drums at the rear of the machine. On either side of the machine is placed a hydraulic jack known as a walking jack for purposes described later. Connected with the motor is a fluid pressure pump from which lead conduits through a valve box at the rear of the machine to the various 40 hydraulic cylinders. The principal controls of the machine are thus located at the rear end where there is the minimum danger of accident to the operator by reason of falling coal or other 45 similar occurrences.

Main base, sub-frame and longitudinal feeding apparatus

Referring to the drawings in detail, 1 is a main base consisting of a plate-like member running the entire length of the machine: on this base 1 is mounted all the principal mechanism of the machine. (See Figures 1, 5, and 23.) Longitudinally along each side of the main base 1 are supporting girders 2 of angular cross section 55 (Figure 11), and these in turn are supported by lower rails 3 secured to their lower edges. Beneath the rails 3 and slidably relatively thereto is the sub-frame or skid plate 4. Running the length of the skid plate 4, adjacent to the base 60 rails 3, are guiding girders 5 secured to which are spacing bars 6 and retaining bars 7. (Figure 11.)

By this arrangement the main base 1 is slidable on the skid plate 4, this being accomplished by a hydraulic cylinder 8 secured to each supporting girder 2 by a web 9. (Figures 8 and 11.) The piston rod 10 of the longitudinal feed cylinder is secured at its outer end to a bracket 11 on the skid plate 4 by nuts 12 on a stud bolt 13. The longitudinal feed cylinder 8 is shown in detail in 70 Figure 43. The cylinder 8 is closed at its rear end by a head 14 into which is threaded a stud bolt 15 with a nut 16 for securing the cylinder to the web 9, as previously described. The head 14 also contains a port 17 which is threaded at its outer 75

end 18 to provide connections with fluid pressure conduits to be described later. The opposite end of the hydraulic cylinder 8 is closed by a head 19 having an opening 20 for the passage of the piston rod 10, the escape of fluid being prevented by a packing 21 adjusted by a screw plug 22 threaded, as at 23, into the head 19. The head 19 contains a port 23 threaded at its outer end 24 for connection with fluid pressure conduits to be described later. The piston rod 10 at its inner end has a portion 25 of reduced diameter threaded at its end 26 to receive a nut 27. On the reduced diameter portion 25 is mounted a piston consisting of five parts: a lower spacer 28, a packing 29, 15 a middle spacer 30, a similar packing 31 and an end spacer 32, the whole being secured in place by the nut 27. When fluid under pressure is admitted through the port 17 to the cylinder 8, it is obvious that the piston will be forced outward, 20 so that the main base 1 and the skid plate 4 will be reciprocated relative to one another, as shown by the dotted lines in Figure 8.

Walking and pivoting apparatus

Arranged at each side of the machine on a cross bracket 33 secured to the main base 1 is a walking jack or walking cylinder 34 (Figure 9) shown in detail in Figure 45. This cylinder has a head portion 35 adjacent to which is located a threaded port 36 for the attachment of a fluid pressure conduit. Within the cylinder 34 is a piston rod 35 having a reduced diameter portion 36 threaded at its outer end to receive a nut 37. The piston itself consists of a lower spacer 38, a packing 39, 30 a middle spacer 40, a packing 41 and an upper spacer 42, the whole being held in place by the nut 37. Near the opposite end of the cylinder 34 is a second threaded port 43 for connection to another fluid pressure conduit. The end of the cylinder 34 adjacent to the port 43 is closed by a flanged head 44 threaded thereto, as at 48. Through an aperture 45 in the flanged head 44, the piston rod 35 is arranged to pass. Escape of the fluid within the cylinder 34 is prevented by 45 the provision of an annular plug 46 and a packing 47 which is clamped tightly into place by the flanged head 44. The walking jack 34 is secured to the cross bracket 33 by means of the flanged head 44. (Figure 9.)

It will be obvious that when fluid under pressure is admitted to the upper end of the cylinder or jack 34, the piston will be forced downward, causing the end 49 of the piston rod to touch the floor of the mine, as shown in Figure 9: if more pressure fluid is admitted, the piston rod 35 will raise the entire machine off the mine floor, except for a slight contact at one end. If now pressure fluid is admitted to the longitudinal feed cylinders 8, as shown in Figure 8, the sub-frame 55 or skid plate 4 will be extended forward beneath the main base 1. (Figures 8 and 10.) If the pressure is then released from the walking jack cylinders 34, the piston rod 35 thereof will be forced upward and the skid plate 4 with the machine on it will again rest on the mine floor in their relatively extended positions. If fluid pressure is now admitted to the longitudinal feed cylinders 8, the main base 1 will be advanced along the skid plate 4 until the two are again in superposition. The operation can be repeated by again forcing liquid into the walking jack cylinders 34, whereby the machine is again raised off the mine floor, the skid plate again extended, the machine then brought to rest on the mine floor 70 as before, and the main base again brought for-

ward into coincidence with the skid plate. In this way the machine may be advanced rapidly with its own self-contained mechanism by a walking or caterpillar-like motion.

By admitting pressure fluid to only one cylinder of the walking jacks, but one side of the machine is raised off the ground: when fluid under pressure is admitted to the longitudinal feed cylinders 8, the machine will be turned sharply around the end 49 of the walking jack 10 piston rod 35 which is in contact with the mine floor.

Vertical feeding and positioning apparatus

On the main base 1 is mounted an upright member 50. (Figure 5.) Pivotedly attached to the upright member 50, as by the bolts 53, is a one-piece vertically movable frame member 51 of very rugged construction in order to withstand the heavy strains imposed thereon by sidewise cutting. Spaced apart from the frame member 51 and pivotally attached to the upright member 50, as by the cross shaft 54, are side bars 52. The cross shaft 54 is mounted in brackets 55 secured by bolts 56 to the upright member 50. The frame 51 and the side bars 52 are linked together at their mid-portions by the mid-connective member 57. The latter is pivotally attached to the side bars 52 by the stub shafts 58 having heads 59, reduced portions 60, locknuts 61 and 30 spacers 62 (Figures 5 and 7). At their forward ends, the frame member 51 and the side bars 52 are additionally linked together by the cutting mechanism support member 97, as will be described later. For reasons which will presently 35 appear, it is important that the separation of the forward pivot points 98 and 102 be somewhat greater than that of the rearward pivot points 53 and 54, the middle pivot points 59 and 69 being separated by an intermediate distance. Thus 40 the side bars 52 are not exactly parallel to the frame member 51.

Joined to the mid-connecting member 57 is a cross member 63 which supports journals 64 for a cross shaft 65. The outer ends of this cross 45 shaft 65 pass through the frame member 51, on the opposite sides of which are arranged yoke members 66 and 67, the whole being held in place by lock nuts 68 on the threaded ends 69 of the cross shaft 65. Through the lower parts of the 50 yoke members 66 and 67 pass yoke pins 70 secured in any suitable way, the means shown being cotter pins through the holes 71. (Figure 7.) The yoke pins 70 serve as a connection for the piston rod cap 72 of the lifting or elevating cylinders 73. (Figures 1 and 5.) The lifting cylinders are shown in detail in Figure 44. By reference thereto, it is seen that the lifting cylinder 73 is closed at its lower end by the end portion 74 which bears a lower link journal 75 for the reception of the cross shaft 54, previously described. (Figure 5.) The cross shaft 54 is held in place by the set screws 76 passing through a boss 77 on the bracket 55. The upper end of the lifting cylinder 73 (Figure 44) is closed by a head cap 78 65 through which passes the piston rod 79. Extending downwardly within the cylinder 73 is a sleeve 80 threadedly secured to an annular plug 81: between the annular plug 81, the piston rod 79 and the head cap 78 is a packing 82 which 70 may be compressed to resist the escape of liquid by turning the head cap 78. The cylinder sleeve 80 contains apertures 83 near its lower free end. The lifting cylinder 73 contains the piston rod 79 which is made hollow by a drilled conduit 84: 75

this conduit 84 communicates by ports 85 to the interior of the cylinder, and by a port 86 to a hollow portion in the interior of the piston rod cap 72. The piston rod cap 72 is secured, as at 5 81, by a threaded connection to the piston rod 79. The piston itself is similar in construction to the other pistons previously described, and bears at its outer end a shaft portion 88 ending in a threaded portion 89 on which is a nut 90. The 10 piston consists of a lower spacer 91, a packing 92, a middle spacer 93, a packing 94 and an upper spacer 95, the whole being held in place by the nut 90. At the lower end of the cylinder 73 is a threaded port 96 for the connection of a pressure 15 fluid conduit.

It will be obvious that when fluid under pressure is admitted through the port 96 into the lifting cylinder 73, the piston head 95, the piston rod 79 and the piston rod cap 72 will be forced 20 upward (Figure 44), thereby swinging the frame member 51 and the side bars 52. (Figure 5.)

Connecting the forward ends of the frame member 51 and the side bars 52 is a cutting mechanism support member 97. (Figure 6.) The 25 frame member 51 is mounted on a shaft 98 passing through the support member 97 and secured against its opposite sides by the nuts 99 on the threaded ends 100 of the shaft 98. Similarly the lower bars 52 are secured against the opposite 30 sides of the support member 97 by the stub shafts 101 having enlarged head portions 102: the stub shafts 101 are reduced in diameter at their opposite ends, as at 103, these ends being threaded to accommodate the lock nuts 104 which hold the 35 assembly together. (Figure 6.) The frame member 51, being of one-piece construction to resist side strains, will also shield the mechanism beneath it from particles of coal or dust. Beneath the side bars 52 is a suitable cradle 134 on which 40 the side bars 52 and their connected parts can rest when dropped to their lowest positions.

Cutter blade tilting mechanism

Midway between the top and bottom of the 45 cutting mechanism support member 97 (Figure 6) is an aperture 106 having a stub shaft 107 which is grooved near its outer end, as at 108, in order to be held in place by a retainer 109 secured to the member 97 by a bolt 110. (Figures 50 6 and 21.) Opposite this stub shaft 107 in the support member 97 is an aperture 111. The stub shaft 107 and the aperture 111 serve as bearing surfaces for the mounting of the cutting mechanism to be described later.

55 In the middle of the lower portion of the support member 97 is incorporated a cutter blade tilting cylinder 112 (Figures 5 and 6) which is shown in detail in Figure 46. Closing the end of the cylinder 112 is the cylinder head 113 held in 60 place by nuts 114 on stud bolts 115. At the opposite end of the cylinder 112 is a stuffing box formed by a packing 116 held in place by a packing ring 117 and adjusted through the agency of the nuts 118 on stud bolts 119. (Figure 46.) 65 Through the packing ring 117 passes the piston rod 120 constricted at its inner end 121 to provide seating for a lower spacer 122, a packing 123, a middle spacer 124, another packing 125 and an upper spacer 126, all held in place by the 70 nut 127 threaded onto the constricted end 121 of the piston rod 120. At the outer end of the piston rod is a piston rod connection 128 having an aperture 129 for the reception of the wrist pin 130 held in place by lock-nutted set screw 75 131. The wrist pin 130 engages a yoke slot 132

in the cutter head base 133 (Figures 3 and 18), which in turn pivots in the aperture 111 and around the stud shaft 107. (Figure 6.)

Thus when pressure fluid is admitted to the cutter head tilting cylinder 112 between the end plate 113 and the upper spacer 126 (Figure 46), the latter, the piston rod 120 and the wrist pin 130 will be forced outward, tilting the cutter head base 133 outward and the cutter blade upward. (Figure 3.) When the pressure fluid is admitted 15 on the opposite side of the piston head in the cylinder 112, the piston will be forced inward, tilting the cutter head and cutter blade downward. As will appear later, the relief valves 533 and 539 in the above-mentioned pressure fluid 20 lines provide a cutter head mounting which will yield and prevent damage under the impact of falling coal, or sudden strains such as would be caused by raising the machine with the cutter blade in the coal seam.

Cutter head and cutting mechanism

The cutter head base 133 (Figure 21) contains a cylindrical bore 135 for the reception of a bushing 136 which receives a correspondingly curved 25 cylindrical extension 137 on the cutter head casing 138: by this arrangement the cutter head may be turned around the axis of the bore 135 so that it can be inverted to occupy the dotted position 30 in Figure 21 and occupy, as desired, the positions shown in Figures 1, 3 or 4. In this manner the cutter head can be adjusted to cut either horizontal or vertical kerfs.

The cutter head is turned as above by means of a worm gear 139 secured to the cutter head 35 casing 138 by cap screws 140, the casing 138 at this point being extended to form a flange 141 which loosely clamps between itself and the worm gear 139 a corresponding flange 142 on the cutter head base 133. Co-acting with the worm gear 40 139 is a worm 143 suitably journaled in tangentially disposed bearings 144 within an extension 145 of the cutter head base 133. The worm shaft 146 passes through the bearings 144 and is squared at its outer end as at 147. A crank 45 with a correspondingly squared socket may be connected with the squared end 147 of the worm shaft 146, and when the crank is turned, the cutter head will be rotated through the action of the worm 143 upon the worm gear 139, around a 50 horizontal longitudinal axis.

The cutter head casing 138 is closed on its upper side by the cutter head casing cover 148 held in place by cap screws 149. Communication with the interior of the casing 138 may likewise 55 be had through a plug 150 in the top of the casing cover 148, as for the introduction of lubricating oil.

The cutter head mechanism receives power from power transmission devices connected with 60 the motor to be described later, these devices ending in the bevel pinion 151 (Figures 12 and 21), and for my present purposes this pinion 151 will be considered temporarily as the source of power for the cutter head mechanism. Meshing 65 with the pinion 151 (Figure 21) is the bevel pinion 152 secured to a tapered portion 153 of the countershaft 154 by means of a key 155 and a nut 156 on a threaded portion 157 thereof. The pinion 152 is provided with an annular portion 70 158 which carries the inner race for an anti-friction bearing 159, the outer race of which is suitably supported in the cupped portion 160 of the countershaft housing 161. The countershaft 154 at its opposite end bears a bevel pinion 162 75

on its tapered portion 163 held in place by a key 164 and a nut 165 on its threaded portion 166. In a manner similar to that of bevel pinion 152, the bevel pinion 162 is supported on anti-friction bearings 167 between itself and the countershaft housing 161. Surrounding the countershaft housing 161 are bushings 168 and 169 separating it from the bore 111 in the cutting mechanism support member 97. The countershaft housing 10 161 continues beyond the bushing 168 into the cutter head base 133, which is separated from the opposite side of the cutting mechanism support member 97 by the collar 170. The portion of the cutter head base 133 adjacent the collar 170 is 15 bored out as at 171 to receive the end of the stub shaft 107 on the axis of stub shaft 107. By this arrangement, the cutter head base 133 is adapted to be tilted vertically (Figures 1, 3, and 4) by means of the cutter head tilting cylinder 112 20 (Figures 5 and 46) in the manner previously described, around the center line of the bore 111 and the stub shaft 107 as an axis of tilt. A plug 172 affords access to the interior of the cutter head base 133, as for inserting a lubricant.

25 Meshing with the bevel pinion 162 is a bevel pinion 173 keyed to its countershaft 174 in the same manner as were the bevel pinions 162 and 152 to the countershaft 154. The countershaft 174 in turn is journaled in anti-friction bearings 175, also accommodated in a similar manner as the anti-friction bearings 167 and 159. The opposite end of the countershaft 174 enters the cutter head casing 138 through an anti-friction bearing 176 arranged between it and the bevel pinion 177 keyed to the countershaft 174 in a similar manner to the bevel pinions 173, 162, and 152.

30 Meshing with the bevel pinion 177 is a bevel gear 178 secured as by the binding rivets 179 to an end plate 180 of a multiple disk clutch; this end plate 180 and the bevel gear 178 being in turn secured to the outer rotor 181 of the clutch. Access to the interior of the clutch is obtained through the removable end plate 182 45 secured to the outer rotor 181 by means of the cap screws 183. The outer rotor 181 is drivingly connected with a plurality of the plates 184 of the multiple disk clutch, the remaining plates being drivingly connected to the inner rotor 185 there- 50 of, which in turn is secured to the cutter head drive shaft 186 by the key 187.

The drive shaft 186 and the inner rotor assembly 184—185 are separated from the outer rotor assembly 178 to 184 by anti-friction bearings 188 and 189, respectively. Pressure tending to force the plates 184 into contact is applied by a number of coil springs 190 disposed in the socketed end plate 182 and around the pins 191. This pressure is set at any predetermined and suitable 60 amount by the number and capacity of the springs used. The inner race of the bearing 188 is held in place by the nut 192 on the threaded portion 193 of the cutter head drive shaft 186.

65 The multiple disk clutch 180 to 191 inclusive serves as a safety device for guarding the mechanism against the shock occasioned by the sudden encountering of a severe stress. When such a shock is received, as when too rapid a cut for the kind of material is being made or a stratum of 0 exceedingly hard material is encountered, or the cutter blade comes into collision with some object, the predetermined pressure in the setting of the springs will be exceeded and the inner rotor assembly of the clutch will slip relatively to the outer rotor assembly and no harm results. As

will be seen later, the hydraulic system of my coal mining machine is also supplied with safety devices in the form of pressure relief valves 533 and 539 which will yield when the encountering of such an obstacle or sudden shock sets up an 5 excessive pressure in the hydraulic circuit. These safety devices serve effectively to protect the machine against such danger.

The cutter head drive shaft continues downward through anti-friction bearings 194 and 195 10 separating it from the cutter head casing 138, and ends in a two-piece sprocket 196—197 held against the enlarged head 198 of the drive shaft 186 by the binding rivet 199. The anti-friction bearings 189 and 194 are separated by the spacer 15 200, and the anti-friction bearing 195 is held in place by the retaining plate 201 secured to the cutter head casing 138 by the cap screws 202.

That portion of the cutter head casing 138 25 which surrounds the cutter head drive shaft 186 is made of a cylindrical shape, and this is surrounded by the bushings 203 which in turn are surrounded by the cutter blade support 204 which is thereby adapted to be swung around the center line of the drive shaft 186 as a transverse axis. (Figure 21.) By this means the cutter blade may be swung angularly into different positions relative to the longitudinal axis of the machine, and locked in place by the agency of the latch 205 (Figure 19), operated by the handle 206 and engaging the slots 207 in the slotted member 208 attached to the cutter head casing 138. The latch itself is held in engagement by means of the coil spring 209 acting upon the plunger 210, the handle 206 being supported on the pin 211. (Figure 21.) Thus by moving the handle 206 the cutter blade support 204 may be swung angularly and the latch dropped into the latch slot 207 next to the desired position. This adjustment is convenient to facilitate working 30 the machine in cramped quarters of certain mine galleries or rooms.

35 Extending outwardly from the cutter blade support 204 is the cutter blade 212, adjustable 40 relatively thereto by spacer bolt 213 and the nuts 214; this adjustment serves to take up slack in the cutter chain. The cutter blade 212 contains a groove 215 around its periphery (Figure 3) in which runs the endless cutter chain 216. The endless cutter chain 216 is composed of individual 50 links having a single tooth 217, each being connected at its front and rear with neighboring links by the pins 218. (Figure 18.) The teeth of the two-part sprocket 196 and 197 (Figure 21) engage the interstices between alternate links 55 of the cutter chain. (Figure 18.) Engaging the threaded portion of the bolt 213 is a correspondingly threaded portion 219 which serves as a nut, and which is secured to the cutter blade bar 212 60 by the binding rivets 220 (Figure 18).

65 When power is supplied to rotate the bevel pinion 151 (Figure 21), the bevel pinion 152 rotates with it, turning the countershaft 154 and the bevel pinion 162, thus rotating the bevel pinion 173, the countershaft 174 and the bevel pinion 177; the rotation of the bevel pinion 177 turns the bevel gear 178, and the torque is transmitted through the multiple disk clutch 180—187 by the engagement of the plates 184 under the pressure of the springs 190. The shaft 186, therefore, rotates, and with it the two-part sprocket 196—197, thereby causing the cutter chain to travel in an orbital path around the groove 215 (Figure 70 3) in the cutter blade 212, as will best be seen from Figure 18.

Electro-mechanical power transmission mechanism

Placed approximately opposite the walking jacks 34 on the main base 1 is an electric motor 221. (Figure 12.) This motor is of any suitable type and is operated by the automatic starter 222 of a conventional type. (Figures 3 and 12.) Electrical energy is transmitted to the machine from a trailing cable 223 (Figure 2), which enters the machine through the trailing cable gland 224. (Figure 16.) The gland 224 is a threaded member engaging a correspondingly threaded portion in the wall 225 of the motor controller housing, and bears a packing 226 at its outer end, against which operates a threaded cap 227; in this manner the motor controller housing is made gas-tight against the entry of inflammable vapors which might be ignited by electric sparks from the controller mechanism. The motor is started and stopped by a push button assembly 228 (Figure 14) mounted within the automatic starter 222 and connected by appropriate wiring to the automatic starter mechanism. Contact with the push buttons 229 of the push button assembly 228 is made through the agency of push-rods 230 pressing thereagainst (Figure 14) and passing outward through the wall 225 of the automatic starter 222 by way of gas-tight gland assemblies 231 similar in construction to the gland assembly 224—227 previously described, through which the trailing cable 223 enters the wall 225 of the automatic starter 222. The outer ends of the push-rods 230 are pivotally mounted in a cross lever 232. (Figure 13.) The cross lever 232 is attached to a stub shaft 233 journaled in bearings 234 and held in place by a bracket 235. The stub shaft 233 bears an arm 236 which is joined to a connecting rod 237 by means of the binding stud 238. The push-rods 230 are kept in a normal position by means of the coil springs 239 acting against the nuts 240. (Figure 12.) The connecting rod 237 proceeds rearward underneath the motor and the other mechanism of the machine (Figure 24), terminating in a crank connection 241 on the end of a vertical shaft 242 journaled in bearings 243, which is actuated by a handle 244 secured to the tapered portion 245 thereof by the nut 246 threaded thereon.

To operate the cutting mechanism, power is transmitted by the motor shaft 247 to the bevel pinion 248 keyed thereto, thence to the bevel pinion 249 keyed to the countershaft 250 having keyed to its opposite end the bevel pinion 251. The motor shaft is journaled in anti-friction bearings 252 and 253, the latter surrounding the pinion 248. The countershaft 250 is journaled in anti-friction bearings 254 and 255 surrounding the bevel pinions 249 and 251 respectively. (Figure 12.) The above gearing is contained in a suitable gear housing 256 having removable end plates 257 and 258.

The outer races of the anti-friction bearings 254 and 255 are journaled in the countershaft housing 259 which is mounted in a horizontal cylindrical bore 260 in the gear housing 256 and separated therefrom by the bushings 261 and 262 held in place by the cap screws 263 and 264. The countershaft housing 259 immediately outside of the bore 260 contains an annular groove 265 in which operates a retainer 266 held in place by the cap screw 267, whereby the countershaft housing is enabled to be turned in the cylindrical bore 260 around the axis of the countershaft 250, but prevented from coming out of the bore 260 by the retainer 266. Perpendicular to the axis of

the countershaft housing 259 is attached power shaft housing flange 268, as by the cap screws 269. The power shaft housing itself consists of the several tubular members 270, 271, and 272, the housing members 270 and 271 being overlapped, with an annular adjustable packing flange 273 and packing 274 to prevent the escape of lubricant. Secured to the forward part of the power shaft housing 272, as by the cap screws 275, is the countershaft housing 161 previously described, the latter being turnably supported in the cutting mechanism support member 97 (Figure 21) and held therein by the retainer 276 secured by the cap screw 277.

Returning to the bevel pinion 251, it will be noticed that it meshes with and transmits power to the bevel pinion 278 keyed to the power shaft 279 which is supported in anti-friction bearings 280 surrounding the hub of the bevel pinion 278, and 281 surrounding the enlarged portion 282 of the shaft itself. A spacer ring 283 separates the anti-friction bearing 281 from the tubular member 270 of the power shaft housing. The power shaft 279 terminates in an externally splined portion 284 which may be engaged or disengaged by the splined sliding sleeve 285 bearing corresponding internal splines 286. The splined sleeve 285 slides to and fro on a correspondingly splined portion 287 of the power shaft extension 288. These parts are held in operative relationship through the action of the spring 289 against the annular plate 290 which abuts against the enlarged portion 291 of the power shaft extension 288. The splined sliding sleeve 285 bears an annular groove 292, which (Figure 20) is engaged by the slider 293 on the slider shaft 294, and this slider in turn is reciprocated by the crank portion 295 on the vertical shaft 296 actuated by the hand lever 297 keyed thereto and held in position by the nut 298 on the threaded portion 299. The crank member 295 engages the slider 293 in a depression 300 therein. The vertical shaft 296 passes through a bored threaded plug 301 which engages corresponding threads in the power shaft housing 272 and compresses therein a packing 302. The hand lever 297 is bored to contain a latch rod 303 operating a latch 304 against the tension of the spring 305 by the latch knob 306. (Figure 20.) The latch 304 engages correspondingly slotted seats 307 in the cutter shaft housing 272.

It will be obvious that when the latch knob 306 is pulled to disengage it from the slots 307, and the hand lever 297 is moved from side to side, the slider 293 will be slid along the slider shaft 294, carrying with it the splined sliding sleeve 285 into engagement with the splined portion 284 on the power shaft 279, thereby drivingly connecting the power shaft extension 288 with the power shaft 279. By manipulating the hand lever 297, therefore, the cutter driving mechanism may be disengaged entirely from its connection with the electric motor 221, and the action of the endless cutter chain 216 completely stopped.

The power shaft extension 288 has keyed on its opposite end the bevel pinion 151, and the whole is supported by anti-friction bearings 308 surrounding the hub of the bevel pinion 151, and 309 surrounding an enlarged portion 310 of the cutter shaft extension 288. (Figure 12).

The bevel pinion 151 meshes with and communicates power to the bevel pinion 152 (Figures 12 and 21), which in turn transmits the power through the transmission shaft, gearing and clutch of the cutter head as previously described

under the sub-title "Cutter head and cutting mechanism". Thus in that preceding section and in the present discussion immediately above, the power connection between the electric motor 221 and the endless cutter chain 216 has been completely traced.

Laterally feeding mechanism and controls

To operate the feeding drums at the rear end 10 of the machine, and thereby move the entire machine bodily, power is communicated to a pinion 311 keyed to the motor shaft 247 (Figure 24), thence to a gear 312 keyed to the stub shaft 313. The stub shaft 313 is mounted in anti-friction 15 bearings 314 and 315, the former surrounding the hub of the gear 312 on the stub shaft 313, the latter surrounding the stub shaft 313 itself. The stub shaft 313 terminates in a pinion 316 integrally secured thereto and this pinion 316 in turn 20 meshes with and communicates power to a gear 317 rigidly secured to a countershaft 318 which in turn is journaled at its opposite ends in anti-friction bearings 319 and 320. A second gear 321 is also rigidly secured to the countershaft 318. 25 (Figure 24.) The anti-friction bearings 314, 315, and 319 are seated in the gear housing 256, whereas the anti-friction bearing 320 is seated in the end plate 322. The countershaft 318 terminates at its opposite end in the pinion 323.

30 Meshing with the gear 321 is a gear 324 (Figure 28) having an axis of rotation around a shaft 325 parallel to the shaft 318. The shaft 325 is journaled at one end in an anti-friction bearing 326 mounted in the countershaft housing 256, and at 35 its other end in an anti-friction bearing 327 mounted in the end plate 322.

The gear 324 is keyed to the outer rotor 328 of a multiple disk clutch, and the outer rotor 328 is separated from the shaft 325 by anti-friction bearings 329 and 330. The outer rotor drivingly engages a plurality of plates 331 of the multiple disk clutch, the remainder of the plates 332 being drivingly engaged by the inner rotor 333 of the multiple disk clutch, said inner rotor 333 being keyed 40 to the shaft 325. The plates are forced into contact by the action of push rods 334 on an annular pressure plate 335 against the action of the springs 336. The opposite end of the push rods 334 is threaded into a shift plate 337 separated 45 by the bushing 338 from the shift sleeve 339 which is splined to the shaft 325.

The shift sleeve 339 also carries at its other end, clutching mechanism identical in construction with the clutching mechanism just described. 50 The clutching mechanism consists of a bushing 340 on which is supported the shift plate 341 into which is threaded the push rods 342 making contact with an annular shift plate 343 against the action of springs 344. The push rods 342 pass through the end plate 345 of the outer rotor 346 of a multiple disk clutch and force the clutch plates 347 drivingly connected to the outer rotor 346 into contact with the clutch plates 348 drivingly connected with the inner rotor 349 of the multiple 55 disk clutch. The inner rotor 349 is keyed to the shaft 325, whereas the outer rotor 346 is separated therefrom by anti-friction bearings 350. Surrounding the outer rotor 346 and keyed to it is the gear 351 (Figure 28) which meshes with the pinion 323 on the shaft 318. (Figure 24.)

Surrounding the shift sleeve 339 at its mid-point is the anti-friction bearing 352 engaged by the yoke portion 353 of the clutch shift rod 354. The clutch shift rod 354 is reciprocable longitudinally 75 by its having at one end a slot 355 engaging a

cap screw 356 threaded through the housing 256, whereas its other end is provided with a right angle portion 357 having a bore 358 slidably engaging a stud bolt 359 threaded through the housing 256. Operatively engaging a bore 360 in the 5 clutch shift rod 354 is the crank portion 361 of a vertical shaft 362 passing through a cover plate 363 in the countershaft housing 256. At its upper end the vertical shaft 362 is provided with a tapered portion 364 which engages a correspondingly tapered portion of a hand lever 365 keyed thereto and held in place by a nut 366 screwed onto the threaded end 367 of the vertical shaft 362. The upper portion of the vertical shaft 362 passes through the valve box brackets 368 and 15 369 which thus support the vertical shaft 362 as well as the valve box to be described later.

The shaft 325 at its inner end is provided with a threaded portion 370 which is engaged by a nut 371 working against a washer 372 which abuts the 20 anti-friction bearing 323, thereby holding the shaft 325 in place. (Figure 28.) The outer end of the shaft 325 passes through an end plate 373 secured to the countershaft housing 256 by the cap screws 374. The end plate 373 contains a spacer 25 375 holding in place the anti-friction bearing 327 and also the packing 376 secured in position by the retainer ring 377. The outer end of the shaft 325 terminates in a pinion 379, here (Figures 27 and 28) shown integral with the shaft 325. 30

On the opposite side of the countershaft housing is a second set of clutches and gearing substantially identical in construction to the clutch-and-gear assembly just described; the entire assembly is shown in plan view in Figure 51, which 35 traces the complete power circuit from the motor 221 and its pinion 311 (both shown dotted) through the various clutches and gearing to the winding drums 392 and 393, described later. The second clutch-and-gear assembly on the shaft 380 40 (Figure 27) has keyed to it a gear 381 (Figures 31 and 51), which meshes with the gear 321 on the countershaft 318. A gear 382 (Figure 51) on the other end of the shaft 380 meshes with the pinion 323 and corresponds to the gear 351 on the shaft 45 325. Since the second set of clutches and gearing on the shaft 380 is of substantially identical construction and operates in a similar manner, further description is unnecessary. The outer end of the shaft 380 terminates in a winding drum 50 pinion 383 analogous to the winding drum pinion 379 on the shaft 325. The clutches 384 and 385 (Figure 51) are operated by the clutch shift rod 386 engaging the anti-friction bearing 387, the clutch shift rod 386 being operated by the vertical 55 crank shaft 388 connected to the hand lever 389 (Figure 26) in a manner similar to that of the hand lever 365 controlling the first set of clutches and gearing previously described.

The gearing and clutch assemblies just described serve as change-speed mechanism to provide two different speeds for the winding drum pinions 379 and 383. When the hand lever 365 is moved to one side (Figure 28) in such a manner that the clutch shift rod 354 is moved backward, 60 the yoke portion 353 thereof likewise moves backward, carrying with it the shift plate 337 which actuates the push rod 334 to press together the plates 331 and 332 of the rearward multiple disk clutch: under these conditions the small gear 324 65 rotatably engages the shaft 325, and a high speed is imparted to the winding drum pinion 379 since the small gear 324 is driven by the gear 321 of almost equal size on the countershaft 318. If, however, the hand lever 365 is moved sidewise in 70 75

the opposite direction, the clutch shift rod 354 moves forward, carrying with it the clutch shift plate 341 which actuates the push rod 342 to compress the plates 347 and 348 of the forward multiple disk clutch, thereby rotatably connecting the large gear 351 with the shaft 325, thus imparting a slower speed to the winding drum pinion 379, since the large gear 351 is now driven by the small pinion 323 on the countershaft 318. In Figure 28, the mechanism is in a neutral state, neither clutch being compressed. The hand lever 389 actuates the right hand clutch assembly on the shaft 380 in a similar manner. This clutch mechanism is enclosed in an oil-tight dust-proof case and has enough disks to permit slippage under load indefinitely, thus providing not only for high and low speeds, but also for intermediate speeds when the clutches are but partially compressed. The cutting speeds may thus be adjusted according to the hardness of the material being cut.

Mesning with the winding drum pinions 379 and 383 are gears 390 and 391 (Figures 25 and 51) secured to similarly-constructed winding drums 392 and 393, as by bolts 394.

The winding drum 392 is rotatably mounted on the flanged winding drum sleeve 395 slidably secured to the winding drum shaft 396 as by the key 397. The flanged winding drum sleeve 395 has a collar 398 which retains the winding drum 392 in position on the winding drum sleeve 395. The collar 398 is held in place by the set screw 399 and lock nut 400 (Figure 25), while between it and the winding drum 392 is the annular plate 401, compressed by the spring 406 to overcome entanglement of the cable 413 due to recoil when the drums are disengaged.

The shaft 396 is journaled in a bore 402 in a boss 403 of the upright member 50 mounted on the main base 1. (Figure 5.) This boss 403 also supports the winding drum gear housing 404 bolted thereto by the angle member 405. Entering into the forward end of the winding drum sleeve 395 are the cap screws 407 (Figures 23, 25, and 51) which are engaged by links 408 attached at their opposite ends by cap screws 409 to an eccentric yoke member 410. The yoke member 410 is supported on a wrist pin 411 which passes through the end of the winding drum shaft 396, the eccentric yoke member 410 being actuated by a hand lever 412. Carried by the winding drum 392 is a cable 413 which at its inner end passes through the inner side flange of the winding drum 392 and is anchored thereto by the anchor block 414 held in position by the bolts 415.

The winding drum shaft 396 immediately back of the winding drum sleeve 395 has an enlarged portion 416 which abuts against the inner end of the winding drum sleeve 395 and also the outer end of the boss 403. When the hand lever 412 (Figure 25) is pulled downward into a horizontal position, the winding drum shaft 396 is pulled backward by the eccentric leverage of the eccentric yoke member 410 acting through the links 408 on the cap screws 407, thereby also pulling backward the winding drum 392 and disengaging the winding drum gear 390 from the winding drum pinion 379. In this way the winding drums 70 may be made to operate as loose pulleys and to pay out the cable 413 without causing the gearing mechanism to rotate. The righthand winding drum 393 is likewise engaged or disengaged from its winding drum pinion 383 by operating the hand lever 417 in the manner previously described

for the corresponding hand lever 412 on the left-hand winding drum 392 (Figure 23).

Cooperating with the winding drums 392 and 393 are vertical sheaves 418 and 419 (Figure 24) serving to guide the cable 413 of the winding drum 392 and the corresponding cable on the winding drum 393. The sheaves 418 and 419 are rotatably mounted on the anti-friction bearings 420 and 421 inwardly supported upon the bushing 422 which is held in position between the sheave supports 423 and 424 by the bolt 425 secured to the base plate 426 mounted on the main base 1 by the bolts 431 (Figure 23). A bolt 427 also cooperates with the bolt 425 to hold together the sheave supports 423 and 424 in spaced relationship with the aid of the spacers 428 and 429 and the partition 430.

The cables coming from the winding drums 392 and 393 are additionally guided by horizontal sheaves 432 and 433 for the lefthand winding drum 392, and 434 and 435 for the righthand winding drum 393. (Figure 23.)

The skid plate 4 (Figure 8) at its forward end carries angle plates 436 and 437 which support (Figure 29) additional sheaves 438 and 439, protected by a guard 440. All of these guiding sheaves are of similar construction and are mounted on similar anti-friction bearings 441. The sheave 438 is held in place by the stub shaft 442 on the threaded end of which is a nut 443. (Figure 29.)

Hydraulic power apparatus and controls

The hydraulic power apparatus in general comprises a pump driven by the motor, a fluid tank in which the pump is located, a valve box 35 containing valves, fluid pressure-operated pistons and cylinders, and conduits completing the hydraulic circuit. The mechanical construction of the various hydraulic cylinders has already been discussed under the various subdivisions 40 of the machine in which these cylinders occur. The pump and valve arrangements, together with the hydraulic circuit, will now be described.

The motor 221 (Figure 12) transmits power through its shaft 247 to the bevel pinion 248 45 keyed thereto. The bevel pinion 248 meshes with and communicates power to a bevel pinion 444 keyed to the pump shaft 445 which is rotatably mounted in an anti-friction bearing 446 held by the pump support 447. The pump support 447 has a cylindrical portion which fits into the cylindrical bore 448 in the housing 256 and is secured thereto by stud bolts 449. The pump 450 is mounted on the pump support 447 and secured thereto by the stud bolts 451. The pump 55 450 itself is seated in a compartment 452 (Figures 12 and 31) leading from the main fluid tank 453, this compartment 452 being closed by the end plate 454 secured thereto by the stud bolts 455, and made liquid tight by the gasket 456.

The pump shaft 445 beyond the anti-friction bearing 446 passes through a plug 457 (Figure 33) against which abuts a washer 458. Against the washer 458 rests a cupped annular retainer for a packing 460 surrounding the shaft 445. The packing 460 is compressed by a spring 461 acting against a washer 462, whereby the escape of fluid along the shaft 445 is effectively prevented. The other end of the spring rests against an annular spacer 463 which encircles 70 a reduced portion 464 of the shaft 445 as it enters the pump 450.

The pump itself is of the gear type, and is shown in Figures 33 and 34. The reduced portion 464 of the shaft 445 is journaled in anti- 75

friction bearings 465 mounted in the front and back walls 466 and 467 of the pump 450. Keyed to the pump shaft portion 464 is a pump gear 468 meshing with a similar pump gear 469 keyed to the countershaft 470 journaled in anti-friction bearings 471 in the housing portions 466 and 467 of the pump 450. The front of the pump housing portion 467 is closed by an end plate 472, the three portions 466, 467 and 472 being held together by stud bolts 451 passing therethrough and seated in the pump support 441. The pump end plate 472 contains, near its lower edge, an inlet port 474 for the entrance of the fluid utilized by the hydraulic system. The pump housing portion 467 on its upper wall similarly contains an outlet port 475. Located in the pump inlet port 474 and correspondingly shaped is an inlet plunger 476 (Figure 31), which by being moved in or out of the port 20 controls the volume of fluid entering the pump. The pump plunger 476 (Figure 12) contains a grooved portion 477 which is engaged by a bifurcated yoke member 478 (Figure 32) keyed to a vertical shaft 479 journaled at the top in a plug 484 screwed into the end plate 454, and at the bottom in a socket 485 in the end plate 454. Secured to the top end of the vertical shaft 479 (Figure 26) is a hand lever 480 which cooperates with a hand lever 481 on the opposite side of the machine by means of a connecting rod 482 pivotally engaging each of these hand levers. By moving either of the pump hand levers 480 or 481, the yoke member 478 causes the plunger 476 to move into or out of the pump inlet port 474, against the action of a spring 483 having its opposite end seated in the end plate 454: in this way the amount of liquid entering the pump is accurately regulated and the speed with which the hydraulic pistons will 35 actuate their respective mechanisms is accordingly varied. Leading upward from the pump outlet port 475 into the main fluid tank 498 is a conduit 486 which terminates in a T connection 481. From one side of this T connection 45 leads a conduit 488 to the entrance port 489 of a safety valve 490. (Figures 30, 31, and 35.) The safety valve 490 consists of a safety valve housing 491 having an inlet chamber 492 communicating with an annular passage 493 surrounding a dumbbell valve plunger 494. The valve plunger 494 is slidable to and fro within a bore 495 against the action of a spring 496, the plunger motion being limited by the adjustable contact rod 499 threaded into the end plug 500 in 50 the safety valve housing 491. Leading outward from the bore 495 are discharge ports 497 communicating with the main fluid tank 498. It will be seen from Figure 35 that when the pressure in the inlet chamber 492 of the safety valve 490 exceeds the predetermined tension regulated by the spring 496, the dumbbell plunger 494 will slide to the left past the discharge ports 497, compressing the spring 496 and coming to rest against the end of the contact rod 499. The excess fluid will now spurt outward through the discharge portion 497 into the main fluid tank until the pressure in the inlet chamber 492 drops back to normal, whereupon the spring 496 will force the dumbbell plunger 494 backward 60 to the right, closing off its communication to the discharge ports 497.

From the remaining side of the T connection 481 leads a conduit 501 through the wall of the main fluid tank 498 and various connections 75 into the inlet port 502 of the valve box 503 (Fig-

ure 30) shown in cross section in Figure 37. The valve box 503 is supported by a pair of angle plates 368 and 369 (Figures 10 and 27) bolted to the side of the countershaft housing 256.

The valve box 503 consists of a valve block 504 of roughly rectangular shape having a plurality of cylindrical bores 505 passing therethrough. Seated in these valve bores 505 are correspondingly curved valve plungers 506 having at each end annular grooves 507 and 508. (Figures 37 and 42.) Each valve plunger 506 seats at one end against a plug 509 in the valve block 504, while at its other end a reduced portion 510 thereof passes through an end plug 511 10 and terminates in a valve handle 512 (designated "Tilt" in Figure 37) secured thereto by the correspondingly squared engaging portions 513 and held in place by the nut 514.

Passing transversely through the valve block 20 504 at its rearward end and communicating with the rearward annular grooves 507 is an inlet chamber 515 and similarly located near the forward end thereof and communicating with the annular portions 508 is an outlet chamber 516. 25 Passing transversely through the valve block 504 above and below the plane of the valve plungers 506 are cross passages 517, 519, 521, and 523 in the upper portion, and 518, 520, 522, and 524 in the lower portion of the valve block 504. (Figure 30 42.) Each of these cross passages 517 to 524 is connected by one of a series of ducts 525 and 526 (Figure 38), 527 and 528 (Figure 39) 529 and 530 (Figure 40) and 531 and 532 (Figure 41). Leading outward from each end of the cross passages 519 to 524 inclusive are fluid conduits 35 communicating with the various pairs of hydraulic cylinders of the machine.

The cross passages 517 and 518 have conduits connected at but one end thereof since this particular valve actuates but one cylinder, namely, the cutter head tilting cylinder 112.

In the cross passage 517 is located a fluid relief valve 533 consisting of a tapered plunger 534 pressed into a conical seat 535 by the action 45 of a spring 536 and reciprocable in a bore 537 of a plug 538. The cross passage 518 contains a similar pressure relief valve 539 of exactly the same construction as the relief valve 533. The relief valves 533 and 539 protect the machine from 50 damage if the cutter blade 212 encounters excessive resistance due to meeting the roof, floor, or other obstacles or to the falls of roof or coal or the upward movement of the machine by the walking cylinders. Such resistance will set up 55 a back pressure in the cutter head tilting cylinder 112 (Figures 5 and 6) and its connecting conduits into either of the cross passages 517 or 518, depending on whether the excess pressure on the cutter blade is upward or downward. When this pressure exceeds a predetermined maximum as controlled by the springs 536, the valve plunger 534 will rise, relieving the pressure by allowing fluid to escape into the adjacent cross passage and permitting the cutter 60 blade to then yield. This device and the multiple disk clutch in the cutter head (Figure 21) prevent damage from excessive vertical and horizontal strains respectively. An additional cushioning effect is provided by the air which gathers in the top portions of the various hydraulic cylinders, the entrance ports of which are 65 purposely located on the sides thereof to allow for this cushioning effect.

Returning to the valve box 503 (Figure 37), it 70

will be seen that each of the valve plungers, of which 506 is a typical example, consists of a cylindrical member with annular grooves 507 and 508 at each end (already described) and with 5 a longitudinally cut-away portion 540 leading from the groove 507 to a point adjacent to the ducts 525 and 526: the opposite side of the valve member 506 has a similar longitudinally cut-away portion 541 leading from the annular 10 groove 508 to a point adjacent to the ducts 525 and 526, as best shown in Figures 37, 52, and 53, where the valve member occupies a neutral position, allowing no fluid to enter either of the 15 ducts 525 or 526. A cross section of this valve member in its neutral position with both ducts 525 and 526 cut off is shown in Figure 38. If now the hand lever 512 be pulled upward (Figure 52) to turn the valve member 506 counter-clockwise through a quarter turn, the passage 20 540 will be brought around to establish communication between the inlet chamber 515 and the duct 526, allowing fluid under pressure to pass therefrom into the cross passage 518, thence (Figure 47) by the conduit 542 into the rearward 25 end of the cutter blade tilting cylinder 112 and causing the piston thereof to move outward, tilting the cutter head and cutter blade upward. The fluid thereby forced out of the forward end of the cylinder 112 returns by the conduit 543 30 to the valve box 503 where it enters the cross passage 517 (Figure 52), passing along the cut-away passage 541 through the annular groove 508 into the outlet chamber 516 and thence by the conduit 543 back through a port 545 in the 35 tank side wall 544 of the auxiliary fluid tank 546: from this auxiliary tank the fluid drops through the strainer 547 into the main fluid tank 453, whereupon it completes the hydraulic circuit.

40 If the hand lever 512 be turned downward (Figure 53), causing the valve member 506 to rotate clockwise through a quarter turn, the longitudinally cut-away passages will be reversed in position: the cut-away passage 540 will communicate with the duct 525, allowing pressure fluid to pass outward through the cross passage 517 and by way of the conduit 543 (Figure 47) into the forward end of the cutter head tilting cylinder 112, where it forces the piston thereof 45 backward, causing the cutter head and the cutter blade to be tilted downward. The fluid forced out of the rearward end of the cylinder 112 returns by way of the conduit 542 to the cross passage 518, passing upward through the duct 526 along the cut-away passage 541 through the annular groove 508 into the outlet chamber 516. Thence the discharged fluid passes by way 50 of the conduit 543 back to the auxiliary fluid tank 546 in the same manner as before, dropping 55 through the strainer 547 into the main fluid tank 453 and thus again completing the hydraulic circuit.

Thus it will be seen that with the lever 512 in the horizontal position (Figure 42), the valve member 506 is in a neutral position, cutting off any communication between either the forward or rearward chambers of the cutter head tilting cylinder 112, locking the fluid in the cylinder and holding the cutter head firmly but yieldably in 60 the position of tilt which it then possesses. By turning the lever 512 upward (Figure 52), the fluid is permitted to enter the rearward chamber of the cylinder 112 and be discharged from its forward chamber, thus tilting the cutter head upward, whereas by turning the lever 512 down-

ward, the flow of fluid is reversed and the cutter head is tilted downward.

The three remaining valve members 548, 549, and 550 (Figure 37) are substantially of the same construction as the valve member 506 previously described: the longitudinal passages 540 and 541 in the valve member 506 become, however, of different relative lengths in the valve members 548, 549, and 550 due to the fact that the cross passages of the latter three valve members are arranged in different positions within the valve box 503, as is clearly shown in Figure 37, which likewise shows the valve members 548, 549, and 550 in their neutral positions. Since each of the valve members 548, 549, and 550 controls the action of a pair of hydraulic cylinders, a connection is provided at each end of the cross passages, instead of the single connection to each of the cross passages 517 and 518 for the valve member 506 which controlled but a single cylinder, namely, the cylinder 112. (Figure 36.) The hand lever 551, designated "Lift" (Figure 37) regulates the valve member 548 which controls the action of the hydraulic cylinders 73: these cylinders 73 serve to elevate or depress the vertically swinging linkage 25 consisting in part of members 51, 52, 57, and 97, to the latter of which the cutter head is attached thereby positioning the cutter blade 212 at any desired elevation to make a horizontal kerf (Figure 3) or else to provide a positive feeding 30 action upward or downward to make a vertical kerf (Figure 4). If the hand lever 551 is pulled upward through a quarter turn counter-clockwise, the longitudinal passage 552 (Figure 37) establishes communication between the inlet chamber 515 and the lower cross passage 520 which transmits fluid (Figure 48) through the conduits 554 and 555 to the rearward chambers of the lifting cylinders 73, causing the pistons 35 thereof to move forward and upward, forcing the discharged fluid back to the valve box through the conduits 556 and 557 to the upper cross passages 519 of the valve box, thence along the longitudinal passage 559 into the outlet chamber 516 and thence back to the fluid tank through the 40 conduit 543.

If the hand lever 551 is pulled downward through a quarter turn clockwise, the flow of fluid is reversed in the same manner as previously discussed with reference to the valve member 506 45 controlling the flow of fluid in the cutter head tilting cylinder 112 and repetition is unnecessary. In this position the pressure fluid will be transmitted from the inlet chamber 515 along the longitudinal passage 552 through the upper 50 cross passage 519 and the conduits 556 and 557 (Figure 48) to the forward chambers in the lifting cylinders 73, causing the pistons thereof to move downward and backward, the discharged 55 fluid escaping back to the outlet chamber 516 by way of the conduits 554 and 555, the lower cross passage 520 and the longitudinal passage 559.

The hand lever 560 (designated "Feed" in Figure 37) similarly controls the action of the longitudinal feed cylinders 8 (Figure 49) through regulating the position of the valve member 549. If the hand lever 560 be pulled upward through a quarter turn clockwise, the longitudinal passage 561 establishes communication between the inlet chamber 515 and the lower cross passage 522, permitting pressure fluid to proceed through the conduits 563 and 564 to the rearward chambers of the longitudinal feed cylinders 8, causing the pistons thereof to move forward: the fluid forced 60 out of the forward chambers of the feed cylinders 70 75

8 returns by the conduits 565 and 566 to the upper cross passage 521, thence along the longitudinal passage 568 to the outlet chamber 516, thence back to the tank by the conduit 543. If the hand lever 560 is pulled downward through a quarter turn counter-clockwise, the flow of fluid and motion of feed is reversed. Under these circumstances, the pressure fluid proceeds from the inlet chamber 515 along the longitudinal passage 561 through the upper cross passage 521 and the conduits 565 and 566 into the forward ends of the longitudinal feed cylinders 8, forcing the pistons thereof backward and causing the fluid in the rearward chamber to be discharged by way of the conduits 563 and 564, the lower cross passage 522, the longitudinal passage 568, the outlet chamber 516 and the discharge conduit 543. By thus manipulating the lever 560, the main base 1 and the sub-frame or skid plate 4 may be moved forward or backward relative to each other.

The hand lever 569, designated "Walk", similarly controls the action of the walking cylinders 34 (Figure 50) by regulating the position of the valve member 550. If the hand lever 569 is pulled upward through a quarter turn clockwise, the pressure fluid is permitted to pass from the inlet chamber 515 along the longitudinal passage 570 into the upper cross passage 523, thence through the conduits 572 and 573 (Figure 50) into the upper chambers of the walking cylinders 34, causing the pistons thereof to move downward and thus lifting the machine substantially off the mine floor: the fluid in the lower chambers of the walking cylinders 34 is discharged through the conduits 574 and 575, the lower cross passage 524, the longitudinal passage 577, the outlet chamber 516 and the conduit 543 leading to the tank 546.

If the hand lever 569 is pulled downward through a quarter turn counter-clockwise, the fluid flow is reversed. Pressure fluid then proceeds from the inlet chamber 515 along the longitudinal passage 570 into the lower cross passage 524, thence through the conduits 574 and 575 to the lower chambers of the walking cylinders 34, forcing the pistons thereof upward and thus lowering the machine into contact with the mine floor: the fluid in the upper chambers of the walking cylinders 34 is meanwhile discharged through the conduits 572 and 573, the upper cross passage 523, the longitudinal passage 577, the outlet chamber 516 and the conduit 543 leading back to the tank 546. The walking cylinders 34 may thus be caused to raise or lower the machine, as desired, by a mere quarter turn of the hand lever 569 either up or down. Furthermore, by opening or closing the individual valves 578 or 579, either one of the walking cylinders 34 may be made inactive, and the other cylinder caused to operate alone through the action of the hand lever 569. In this way the machine may be tilted up on one side and the longitudinal feeding cylinders regulated to cause the machine to turn sharply around the piston of the walking cylinder 34 as a pivot.

Operation summarized

The operation of the various parts of the machine has been more conveniently described under each of the subdivisions which dealt with that particular part of the machine. A general summary of the operation of the coal mining machine will now be made.

The machine is preferably transported over considerable distances within the mine by being

carried on an ordinary mining truck which moves on the usual rails laid in the various passages of the mine. Such a truck forms no part of the present invention. The machine may be drawn up on the truck by hooking the ends of the cables 413 to the truck, starting the motor by shifting the hand lever 244 (Figure 2) and causing either of the winding drums 392 or 393 to be put into operation by moving the hand levers 365 or 389 respectively. Similarly the machine may be moved off the truck by hooking the end of the cable 413 to an anchor jack, operating the winding drums and pulling the machine toward the anchor jacks. In each case the cable is guided by the sheaves 418 and 419, also by such of the 15 sheaves 434, 435, 433, 432, 439, and 438 as may be most convenient in the particular instance.

In bringing the machine up to the face of the coal bank in the mine chamber, it is most convenient to use the walking jack devices in combination with the longitudinal feeding devices as previously described. The walking jacks are operated by moving the hand lever 569 upward, raising the machine bodily off the mine floor. The hand lever 560 is then pulled upward through 25 a quarter turn, causing the pistons in the longitudinal feed cylinders 8 to move forward, extending the sub-frame or skid plate 4 attached thereto, whereupon the hand lever 560 is returned to its neutral position. The hand lever 569 is now 30 pulled downward through the neutral position into reverse position, causing the pistons in the walking cylinders 34 to move upward and bringing the skid plate 4 to rest on the mine bottom, whereupon the hand lever 569 is returned to the 35 neutral position. The hand lever 560 is now moved downward a quarter turn, causing fluid to enter the forward chambers of the longitudinal feeding cylinders 34, causing them and the main base 1 connected together to be pulled forward 40 along the skid plate 4, whereupon the hand lever 560 is returned to its neutral position.

This alternate use of the walking and feeding cylinders to advance the machine may be repeated as often as desired, causing the machine 45 to travel rapidly over the mine floor. If it is desired to turn the machine during its forward advance, this may be done quickly and sharply by closing one of the hand auxiliary valves 578 or 579 as the case may be, to put one of the walking cylinders 34 out of action and manipulate the hand lever 569 to cause one side of the machine to be lifted off the mine floor. The hand lever 560 is then manipulated to put the longitudinal feeding cylinders 8 into action, causing 50 the machine to pivot sharply around the piston of the walking cylinder 34 which is in contact with the mine floor.

When the machine has advanced as far as the mine wall, the same walking motion may be used 60 during the sumping cut which buries the cutter blade 212 deep within the coal bank. The skid plate 4 is first advanced as far as possible by the use of the walking cylinders 34 and the longitudinal feeding cylinders 8, whereupon the latter are set in motion to advance the main base 1 and the cutting mechanism carried by it forward along the skid plate 4, feeding the cutter blade into the wall of the coal seam, the endless 65 cutter chain 216 having been previously set in motion by moving the hand lever 297 (Figure 20) to engage the sections of the power shafts 219 and 288. When the main base 1 has been brought completely over the skid plate 4, the latter is 70 75

again advanced by operating the walking jacks, and the feeding process again repeated.

The speed of feeding in any direction is regulated by the hand lever by moving sidewise either 5 of the hand levers 480 or 481 (Figure 2), thereby causing the plunger 476 to move in or out of the pump inlet port 474 (Figure 31), thereby increasing or decreasing the amount of fluid entering the pump and hence varying the rate at which 10 the liquid will be transmitted to the various hydraulic cylinders.

With the sumping cut completed, assuming that a vertical sump has been made as in Figure 4, the vertical or shearing kerf may now be completed 15 by pulling the hand lever 551 downward a quarter turn: this causes pressure fluid to enter the forward chambers of the lifting cylinders 73, causing their pistons to be retracted, and drawing downward the upper vertical swinging frame member 51 to which they are attached (Figure 4). The speed of feeding is meanwhile regulated by 20 manipulating the pump control lever 480 or 481 (Figure 2) until the lowest position of the cutter blade has been reached. The cutter blade may 25 then be withdrawn from the kerf by using the walking jacks 34 and the longitudinal feed cylinders 8 in the manner previously described.

To cut a horizontal kerf, such as is shown in Figure 1, the cutter blade is brought down to its 30 lowest position by manipulating the hand lever 551 of the lifting cylinders 73, and locked in that position by turning the hand lever 551 into its neutral position. The cutter blade is turned so that the plane of the cutter blade is horizontal 35 by attaching a hand crank to the squared end 147 of the worm shaft 146 (Figure 18). Turning the crank revolves the worm, 143, turning the worm gear 139 secured to the cutter head casing 138. The horizontal sumping cut is now accomplished, like the vertical one previously described, 40 by operating the walking cylinders 34 and the longitudinal feed cylinders 8.

To move the machine laterally, such as in cutting, and make the bottom horizontal kerf, the 45 winding drums 392 and 393 are used, the cables 413 therefrom being attached to anchor jacks located at a distance, and guided by the sheaves 438 and 439 (Figure 2). By moving the hand levers 365 and 389, either of the winding drums 50 may be set in motion at any of the speeds provided by the transmission gearing or slipping clutches. The winding drum 393 winds in one cable, while the other winding drum 392 pays out the other cable. The skid plate 4 may be advanced 55 forwardly or rearwardly of its mid-position (shown in dotted lines in Figure 2) by whatever amount is necessary to maintain the proper angle of the mining machine relative to the coal bank. This is done by using the walking cylinders 34 60 and/or the longitudinal feed cylinders 8, and avoids the need of using a retarding cable at the rear end of the machine.

To cut a top kerf (Figure 3) the cutter head is inverted by hand cranking the worm shaft 146, 65 thus rotating the worm 143 and the worm gear 139 attached to the cutter head casing 138. The cutter blade is then raised to the roof position (Figure 3) by causing the lifting cylinders 73 to raise the cutter head support 97. In practice 70 the cutter blade has a tendency not to closely follow the top and bottom limits of the coal seam. To overcome this, the forward pivot points 100 and 101 of the vertical swinging frame have been spaced a slightly greater distance apart than the 75 pivot points 53 and 54 at the rear end thereof,

causing the cutter blade to tilt downward as the vertically swinging frame is lowered and to tilt upward as the latter is raised. By thus having this tilting movement automatically take place, the operator is not always required to use the 5 tilt cylinder 112 for the vertical positioning of the blade with respect to the roof and floor of the coal seam.

If the floor of the mine happens to slope relative to the face of the coal seam, or if for any 10 reason it is desired to tilt the cutter blade through a greater angle than that resulting from the differential spacing of the pivot points 53, 54, 98, and 102, the hand lever 512 is moved to cause the 15 cutter head tilting cylinder 112 to tilt the cutter head attached to its piston.

If it is found more convenient to use the machine with its longitudinal axis at an angle to its cutter blade axis, as in cramped working quarters, this may be done by lifting the latch lever 205 20 (Figures 1 and 21) and swinging the machine bodily by means of the winding drums, by allowing the latch connections to drop into one of the latch slots 207 (Figure 19) when the desired 25 angling has been obtained. The machine can then be maneuvered by the controls previously described until it comes to rest alongside of the face of the coal bank. The various kerfs may then be cut as previously described.

The machine may be turned on or off at any 30 time by moving the hand lever 244, controlling the push button switches in the automatic starter 222 (Figure 3). The latter is gas-tight, hence any sparking which might occur at the contact points of the push button will be harmless. 35

It will be understood that I desire to comprehend within my invention such modifications as may be necessary to adapt it to varying conditions and uses.

Having thus described my invention, what I 40 claim as new and desire to secure by Letters Patent is:

1. A mining machine comprising a skid plate, a main base mounted on said skid plate and reciprocable relatively thereto, elevating mechanism comprising a linkage mounted on said main base, cutting devices supported on said linkage, a power source drivingly connected with said cutting devices, means mounted on said main base for raising a portion of said main base 50 with respect to the mine floor and means for reciprocating said skid plate relative to said main base while said main base is in said raised position.

2. A mining machine comprising a skid plate, 55 a main base mounted on said skid plate and reciprocable relatively thereto, elevating mechanism comprising a linkage mounted on said main base, cutting devices supported on said linkage, a power source drivingly connected with 60 said cutting devices, means comprising hydraulic cylinders mounted on said main base for raising a portion of said main base with respect to the mine floor, and means comprising hydraulic cylinders for reciprocating said skid plate relative to said main base while said main base is in said raised position, said hydraulic cylinders being connected to a source of fluid pressure.

3. In a mining machine, a skid plate, a main base reciprocably mounted relative to said skid 70 plate, raising and lowering devices mounted on said main base for raising and lowering the latter, and means for reciprocating said skid plate relative to said main base when the latter is raised.

4. In a mining machine, a skid plate, a main base reciprocably mounted relative to said skid plate, raising and lowering devices comprising hydraulic cylinders mounted on said main base
- 5 for raising and lowering the latter, and means comprising hydraulic cylinders for reciprocating said skid plate relative to said main base, whereby said skid plate may be advanced relative to said main base when said raising and lowering
- 10 devices are operated to raise a portion of said mining machine out of contact with the mine floor.
5. In a mining machine, a skid plate, a main base reciprocably mounted relative to said skid plate, raising and lowering devices mounted on
- 15 said main base for raising and lowering the latter, means for reciprocating said skid plate relative to said main base when the latter is raised, and means for operating said raising and lowering devices independently of one another.
- 20 6. In a mining machine, a skid plate, a main base reciprocably mounted relative to said skid plate, raising and lowering devices comprising hydraulic cylinders mounted on said main base for raising and lowering the latter, means for
- 25 reciprocating said skid plate relative to said main base when the latter is raised, and means for operating said raising and lowering devices independently of one another.
7. In a mining machine, a skid plate, a main
- 30 base reciprocably mounted relatively to said skid plate, raising and lowering devices mounted on said main base to raise said skid plate and tilt it relative to the mine floor, and means operative when said skid plate is raised and tilted for
- 35 reciprocating said skid plate relative to said main base.
8. In a mining machine, a skid plate, a main base reciprocably mounted relative to said skid plate, a pair of raising and lower devices for
- 40 the skid plate and base mounted one on each side of said main base and supported thereby, and means operative when said skid plate and base are raised for reciprocating said skid plate relative to said main base.
- 45 9. In a mining machine, a skid plate, a main base reciprocably mounted relative to said skid plate, a pair of raising and lowering devices for said main base mounted one on each side of said main base and supported thereby, means for reciprocating said skid plate relative to said main base when the latter is raised, and means for operating each of said raising and lowering devices independently of one another.
10. In a mining machine, a skid plate, a main
- 55 base reciprocably mounted relative to said skid plate, a raising and lowering device for the skid plate and said main base mounted on each side of said main base near a mid-section thereof, said devices operative to raise and lower said skid
- 60 and main base simultaneously substantially off the mine floor, and means for operating said raising and lowering devices.
11. In a mining machine, a skid plate, a main base reciprocably mounted relative to said skid
- 65 plate, a raising and lowering device mounted on each side of said main base near a mid-section thereof, said devices operative to raise said base to relieve substantially the weight thereof from said skid plate, and means for operating said
- 70 raising and lowering devices independently of one another.
12. A method of advancing and retracting a machine having longitudinally relatively movable sections, comprising raising a part of the
- 75 machine, including at least a part of each of said sections, out of contact with the supporting material, and moving one of said sections of the machine relative to the other while the said part of the machine is so raised.
13. A method of advancing and retracting a 5 machine having relatively movable sections one supported by the other, comprising raising a part of the machine, including at least a part of each of said sections, out of contact with the supporting material, moving one section of the 10 machine longitudinally relative to the other while the said part of the machine is so raised, lowering the raised part of the machine into contact with the supporting material, and moving the supported section on the supporting section. 15
14. A method of advancing and retracting a machine having relatively movable sections, comprising raising a part of the machine, including at least a part of each of said sections, out of contact with and into tilted relation to the 20 supporting material, and moving one of the sections of the machine relative to the other while the said part of the machine is so raised and tilted.
15. A method of advancing and retracting a 25 machine having relatively movable sections one supported by the other, comprising raising a part of the machine, including at least a part of each of said sections, out of contact with the supporting material and into tilted relation to the sup- 30 porting material, moving one section of the machine relative to the other while the said part of the machine is so raised and tilted, lowering the machine into full contact with the supporting material and moving the supported section on 35 the supporting section.
16. A method of advancing and retracting a machine having movable sections, comprising raising a part of the machine, including at least a part of each of said sections, near the center of 40 gravity thereof out of contact with the supporting material and moving one relatively movable section of the machine relative to the other while the said part of the machine is so raised.
17. A method of turning a machine having 45 relatively movable sections, comprising raising one side of the machine, including at least a part of each of said sections, out of contact with the supporting material, and moving one of said sections of the machine relative to the other, thereby pivotally swinging said machine around its remaining point of contact with said supporting material. 50
18. A method of turning a machine having relatively movable sections, comprising raising 55 one side of the machine near its mid-point out of contact with the supporting material and providing a pivotal point of support with the material only adjacent said mid-point, and moving one section of the machine relative to the other 60 so as to swing said machine pivotally around said mid-point support on said supporting material.
19. A method of moving and turning a machine having relatively movable sections, comprising raising one side of the machine partially out of contact with the supporting material at a point near the center of gravity of said machine and providing a pivotal point of support with the material only adjacent said mid-point, and moving one section of the machine 70 relative to the other while pivoting around the supporting point of the side of the machine so raised.
20. In combination, in a hydraulic control sys- 75

tem for a coal mining machine movable over a mine floor, a coal cutting tool, means for operating said coal cutting tool, a fluid pressure pump, a hydraulic cylinder for horizontally moving said cutting tool, a hydraulic cylinder for vertically moving said cutting tool, a hydraulic cylinder for tilting said cutting tool, a hydraulic cylinder for selectively raising the complete coal mining machine substantially from the mine floor and for lowering the machine onto the mine floor, and conduits for conducting pressure fluid between said fluid pressure pump and said hydraulic cylinders.

21. A mechanism for hydraulically controlling a coal mining machine movable over a mine floor, comprising means for placing fluid under pressure, and means for selectively causing said pressure fluid to actuate a horizontal feeding piston, a vertical feeding piston, a cutter tilting piston, and a machine raising piston for bodily raising the complete machine substantially from the mine floor, whereby the cutter of said coal mining machine is hydraulically adapted to move in a plurality of directions.

22. In combination, in a hydraulic control system for a coal mining machine movable over a mine floor, a coal cutting tool, means for operating said coal cutting tool, a fluid pressure pump, a hydraulic means for horizontally moving said cutting tool, a hydraulic means for vertically moving said cutting tool, a hydraulic means for tilting said cutting tool, a hydraulic means for selectively raising the complete coal mining machine bodily substantially from the mine floor and for lowering the machine onto the mine floor, and conduits for conducting pressure fluid between said fluid pressure pump and all of said hydraulic means.

23. A mechanism for hydraulically controlling a coal mining machine movable over a mine floor comprising means for placing fluid under pressure, and means for selectively causing said pressure fluid to actuate a horizontal feeding means, a vertical feeding means, a cutter tilting means, and

45 a machine raising means for bodily raising the complete mining machine substantially from the mine floor, whereby the cutter of said coal mining machine is hydraulically adapted to move in a plurality of directions.

50 24. In a mining machine, a skid adapted to rest upon and slide in any direction over the mine floor, an arm structure pivotally mounted at its rear end at the rearward portion of said skid to swing in a vertical direction relative thereto, said

55 arm structure overlying said skid, a support carried at the outer extremity of said arm structure, a cutter head mounted on said support for rotation with respect thereto about a horizontal axis, and a kerf cutter pivotally mounted on said cutter 60 head to swing relative thereto and adjustable with said cutter head about the head axis while the latter remains horizontal into horizontal and vertical cutting positions, said cutter head being rotatable as aforesaid to move the kerf cutter into 65 said horizontal and vertical cutting positions irrespective of the adjusted position of said arm structure about its pivot relative to said skid.

25. In a mining machine, a skid adapted to rest upon and slide in any direction over the mine 70 floor, an arm structure pivotally mounted at its rear end on the rearward portion of said skid to swing in a vertical direction relative thereto, said arm structure overlying said skid, a support carried at the outer extremity of said arm structure, 75 a cutter head rotatably mounted on said support

a kerf cutter pivotally mounted on said cutter head to swing relative thereto, and means for tilting said support with respect to said arm structure to vary the angular position of the head axis.

26. In a mining machine, a skid adapted to 5 rest upon and slide in any direction over the mine floor, a base guided on said skid to slide longitudinally relative thereto, a substantially parallel motion arm structure pivotally mounted at its rear end on the rearward portion of said base to swing 10 in a vertical direction relative thereto, said arm structure overlying said base, a support carried at the outer extremity of said arm structure, a cutter head rotatably mounted on said support, 15 and a kerf cutter pivotally mounted on said head to swing relative thereto and adjustable with said head about the head axis into horizontal and vertical cutting positions.

27. In a mining machine, a skid adapted to 20 rest upon and slide in any direction over the mine floor, a base guided on said skid to slide longitudinally relative thereto, a substantially parallel motion arm structure pivotally mounted at its rear end on the rearward portion of said base to swing 25 in a vertical direction relative thereto, said arm structure overlying said base, a support carried at the outer extremity of said arm structure, a cutter head rotatably mounted on said support, a kerf cutter pivotally mounted on said head to swing relative thereto and adjustable with said head 30 about the head axis into horizontal and vertical cutting positions, and means for tilting said support with respect to said arm structure to vary the angular position of the head axis.

28. In a mining machine, a structure supporting 35 cutting means, and means for feeding said supporting structure comprising walking jacks and a sliding supporting frame, said frame when said jacks are inoperative providing for sliding feed of the supporting structure, said jacks when operative lifting the weight of the supporting structure 40 off from said sliding frame so that the latter may be slid while the supporting structure remains stationary in its lifted position.

29. In a mining machine, cutting devices, and a 45 rectilinear feed for said cutting devices comprising a base on which said cutting devices are slidably guided, said cutting devices sliding relative to said base during rectilinear feed, and means for lifting said cutting devices to relieve said base of 50 the weight of said cutting devices, said means relieving the base from the weight of the cutting devices during movement of the base into a new feeding position.

30. In a mining machine, a base, substantially 55 parallel arms pivotally mounted on said base to swing in a vertical direction relative thereto about parallel horizontal axes, a cutter mounted on the outer extremities of said arms, and a hydraulic cylinder and piston device for swinging said arms 60 relative to said base, said device comprising cooperating cylinder and piston elements, one of which is pivotally connected to one of said arms and the other pivotally mounted on an axis coincident with one of said parallel horizontal arm pivot 65 axes.

31. In a mining machine, a machine walking 70 device comprising means for sliding the machine, lifting the machine and thereafter when the machine is so lifted moving the sliding means to a new feeding position, the weight of the machine being relieved from said sliding means during such sliding of the latter into a new feeding position.

32. In a mining machine, a means for feeding 75 the machine comprising a base, a frame thereon,

means for sliding said frame relative to said base, means for raising the frame to relieve the weight of said frame from said base, and means for sliding said base relative to said frame when the latter is so raised.

- 5 33. In a mining machine, a skid adapted to rest upon and slide in any direction over the mine floor and having a longitudinal guideway, a main base reciprocable on said skid guideway, 10 elevating mechanism comprising a vertically swingable arm structure pivotally mounted on said main base, a kerf cutter supported on said arm structure, means for driving said kerf cutter, means for swinging said arm structure and 15 for reciprocating said main base along the skid guideway to effect rectilinear summing, swinging, and rectilinear withdrawal movements of said kerf cutter, means for bodily feeding the machine over the mine floor in an endwise direction to 20 ward and from the working face, and means distinct from said base reciprocating and endwise machine feeding means for feeding the machine bodily laterally over the mine floor transversely relative to the working face.
- 25 34. In a mining machine, a skid adapted to rest upon and slide in any direction over the mine floor and having a longitudinal guideway, a main base reciprocable on said skid guideway, 30 elevating mechanism comprising a vertically swingable arm structure pivotally mounted on said main base, a kerf cutter supported on said arm structure and adjustable into horizontal and vertical cutting positions, means for swinging said arm structure and for reciprocating said 35 main base along said skid guideway, when said kerf cutter is in vertical cutting position, to effect rectilinear summing, vertical swinging, and

rectilinear withdrawal movements of said kerf cutter, means for bodily moving the machine over the mine floor in an endwise direction toward and from the working face, and means distinct from said base reciprocating and endwise machine feeding means for feeding the machine bodily over the mine floor, when the kerf cutter is in horizontal cutting position, to effect horizontal rectilinear feed of said kerf cutter transversely relative to the working face.

10 35. In a mining machine, a skid adapted to rest upon and slide in any direction over the mine floor, an arm structure pivotally mounted at its rear end on the rearward portion of said skid to swing in a vertical direction relative thereto, 15 said arm structure overlying said skid, a support carried at the outer extremity of said arm structure, a cutter head rotatably mounted on said support, and a kerf cutter pivotally mounted on said cutter head to swing relative thereto, said 20 arm structure being adjustable to vary the elevation of said support to position the head axis in different horizontal planes.

36. In a mining machine, a frame adapted to rest upon and slide in any direction over the mine 25 floor, an arm pivotally mounted on said frame to swing in a vertical direction relative thereto, a cutter support pivotally mounted on the outer extremity of said arm, a kerf cutter carried by said cutter support and pivotally mounted thereon to swing relative thereto, said kerf cutter swingable with the cutter support into relatively inclined cutting planes, and motor operated means for actuating said kerf cutter, for swinging said arm relative to said frame and for swinging said cutter support relative to said arm.

JOSEPH F. JOY.

CERTIFICATE OF CORRECTION.

Patent No. 2,062,657.

December 1, 1936.

JOSEPH F. JOY.

It is hereby certified that error appears in the printed specification of the above numbered patent requiring correction as follows: Page 8, first column, line 69, for "widing" read winding; page 13, first column, line 39, claim 8, for "lower" read lowering; and second column, line 66-67, claim 19, strike out the word "partially"; page 14, first column, line 9, claim 20, after "machine" insert bodily; and that the said Letters Patent should be read with these corrections therein that the same may conform to the record of the case in the Patent Office.

Signed and sealed this 5th day of October, A. D. 1937.

Henry Van Arsdale
